(57)

CLAIM

The ornamental design for a chest as shown and described.

DESCRIPTION

FIG. 1 is a top, front, right perspective view of a chest showing our new design;

FIG. 2 is a bottom, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the Figures depict portions of the chest that form no part of the claimed design.

1 Claim, 8 Drawing Sheets
